SWING

Marshall L. Carraway, Malvern, Ark.

Application January 25, 1935, Serial No. 3,519

1 Claim. (Cl. 155—65)

The device forming the subject matter of this application is a swing, adapted to be used indoors, primarily, in bad weather, to give exercise to children, although the swing may be used outdoors as well. The invention aims to provide a device of the class described which may be manufactured at small cost, be ornamented by painting or any other simple method, and be readily portable. The invention aims, further, to supply a device of the class described which will operate with little friction, it being possible to impart swinging movement to the hanger, by means of a light pull. The device comprises a frame, a hanger carried by the frame, means on the frame for accommodating an occupant, and means for imparting swinging movement to the hanger.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawing:

Fig. 1 shows in side elevation, a device constructed in accordance with the invention, parts being broken away;

Fig. 2 is an elevation wherein the device is viewed at right angles to the showing of Fig. 1.

The device forming the subject matter of this application preferably is made, for the most part, out of wood. It comprises a frame, which, as a whole, is marked by the letter F. The frame F comprises legs 1. As shown in Fig. 1, the legs 1 diverge from front to back, and as shown in Fig. 2, they diverge from side to side. The upper ends of the legs 1 are beveled as shown at 2, to rest against opposite sides of a top bar 3. The lower edge of the top bar 3 slants upwardly from the ends of the top bar to the intermediate portion thereof. Securing elements 5 of any desired kind, for instance bolts, connect the upper ends of the legs 1 to the top bar 3. About midway between their upper and lower ends, the legs 1 are connected at the sides of the frame F by rigid ties 6, held on the legs 1 by securing devices 7. A rigid, forwardly extended, horizontal arm 8 has its rear end resting on the upper edge of

the top bar 3. The rear end of the arm 8 is held on the intermediate portion of the top bar 3 by a bolt 9. The bolt 9 has an eye 10 at its lower end, and the eye 10 engages the lower edge of the top bar 3. A nut 11 is threaded on the upper end of the bolt 9. A washer 12 is interposed between the nut 11 and the arm 8. Noting that the lower edge 4 of the top bar 3 slants upwardly from the ends of the top bar to the middle portion thereof, the top bar is narrowest in its middle portion. The bolt 9, consequently, may be made shorter than would be the case otherwise, and the bolt is increased in strength accordingly. The bolt 9 serves two purposes. It holds the arm 8 on the top bar 3 and also forms part of the suspension means for the hanger H.

The hanger H is of inverted U-shape. The hanger H includes a top piece 14 located below the top bar 3 and disposed at right angles to the top bar. Rigid, vertical front strips 15 and rigid vertical rear strips 16 are provided. The front strips 15 are longer than the rear strips 16. The forward end of the top piece 14 is disposed between the upper ends of the front strips 15, and the rear end of the top piece 14 is disposed between the upper ends of the rear strips 16. The upper ends of the front strips 15 and the upper ends of the rear strips 16 are secured rigidly to the ends of the top piece 14 by securing elements 17. A hook bolt 18 is mounted in the top piece 14 of the hanger H, at a point midway between the ends of the top piece. The hook bolt 18 is held in the top piece 14 by a nut 19. A washer 20 is interposed between the nut 19 and the lower edge of the top piece 14. The hook portion of the bolt 18 is arranged at right angles to the eye 10 of the bolt 9 and is pivotally and detachably engaged with the eye 10. The hanger H, therefore, is mounted on the frame F for backward and forward swinging movement in the direction of the arrows in Fig. 1.

The hanger H carries a means M for supporting an operator. That means may comprise a body 21, shaped like a horse or any other animal, or constructed otherwise. A seat 22 is secured to the upper edge of the body 21, intermediate the ends of the body. The body 21 is located between the front strips 15 of the hanger H and between the rear strips 16 of the hanger. The body 21 is connected to the strips 15 and 16 by securing devices 23. The front strips 15 extend downwardly a little way below the body 21. If the body 21 is made to simulate a horse, the head portion of the part 21 may carry a flexible element 24, representing a bridle. Those

portions of the front strips 15 which extend downwardly below the body 21 carry, securely mounted, a transverse peg 25, constituting a lower foot rest. The front strips 15 carry, also, a similar upper foot rest 26, disposed above the lower foot rest 25. The reason for having two foot rests is to accommodate the device to children of different statures. The upper foot rest 26 passes through the body 21, and aids in holding the body on the front strips 15. A transverse peg 27 is mounted in the front strips 15, above the body 21 and constitutes a hand grip for the person occupying the seat 22.

An operating member 28 is provided. The operating member 28 preferably is a rigid strip. The upper end of the operating member 28 is pivotally connected, by means of a link 29 and an eye bolt 30, with the forward end of the arm 8. The operating member 28 is downwardly and rearwardly inclined, and passes slidably between the front strips 15 of the hanger H. A transverse handle 31 is mounted in the lower end of the operating member 28. The handle 31 is located behind the front strips 15 of the hanger H and slides up and down on the rear edges of the front strips 15. The handle 31, in view of the foregoing, is always kept in an accessible position for the person occupying the seat 22.

The operation of the device is simple. The operator places his hands on the handle 31, and by exerting a slight pull, the hanger H is caused to swing back and forward in the direction of the arrows in Fig. 1. If the operator wishes, he can release the handle 31 and grip the handle 27 that is carried by the front strips 15 of the hanger H. Owing to the way in which the hanger

H is suspended at 10-18, and owing to the specific arrangement of the arm 8 and the operating member 28, the hanger H may be caused to swing back and forth with a very small expenditure of effort on the part of the person occupying the seat 22. The foot rest 25, or the foot rest 26, of course enables the operator to brace himself, whilst using the device.

Having thus described the invention, what is claimed is:

A swing comprising a frame, a forwardly presented arm carried by the top of the frame, a hanger of inverted U-shape and comprising a pair of depending front strips and a depending rear strip, means secured to the rear strip and to the front strips for carrying an operator, means for suspending the hanger at its top from the top of the frame for swinging movement, an operating member pivoted at its upper end to the forward portion of the arm, the operating member extending downwardly and backwardly between the front strips, the front strips being located close enough together to prevent the operating member from having any appreciable lateral swinging movement, and a handle on the operating member and slidable up and down on the rear edges of the front strips when the hanger is in motion and when the operating member is not in use, the handle being kept in such a position that it is accessible to a person occupying the seat 22.

MARSHALL L. CARRAWAY.
